UNITED STATES PATENT OFFICE.

CHARLES L. BUCKINGHAM, OF NEW YORK, AND EMIL GERMANN, OF BROOKLYN, NEW YORK; SAID GERMANN ASSIGNOR TO SAID BUCKINGHAM.

PRINTING-TELEGRAPH.

SPECIFICATION forming part of Letters Patent No. 544,347, dated August 13, 1895.

Application filed January 10, 1895. Serial No. 534,480. (No model.)

To all whom it may concern:

Be it known that we, CHARLES L. BUCKINGHAM, a resident of New York, in the county of New York, and EMIL GERMANN, a resident 5 of Brooklyn, in the county of Kings, State of New York, citizens of the United States, have invented certain new and useful Improvements in Printing-Telegraphs, of which the following is a specification.

10 The present invention relates mainly to a modification in the construction of electric devices termed "sunflowers," and which as ordinarily constructed have a rotating arm, which carries a circuit-closing spring over a 15 ring of insulated contacts for the purpose of closing in rapid succession a number of separate circuits or branches. Such a device is employed in many situations and in some cases, as, for instance, in the printing-telegraph system patented to Charles L. Buckingham December 18, 1892, No. 487,982, wherein 20 it is employed to close in succession the circuits of selector-relays which govern the action of type-wheel-adjusting devices, must operate at very high speed.

Our present invention consists mainly in a novel construction of electric distributor applicable for use in the printing-telegraph system referred to, as well as in other situations, 30 and is designed to produce an instrument not only capable of operation at high speed, but also compact and reliable in operation and accessible and convenient for repair.

Other parts of the invention relate to the 35 unison-stop devices for the distributor, whereby it may be caused to always begin its cycle of changes at the same or zero point, to the means for securing a rapid action of the magnetic devices which operate the escapement 40 devices for the distributor, and to local-circuit arrangements of the several magnets which vibrate the escapement, control the unison-stop, and govern the action of the relay-magnets, whose circuits are closed in succession by the distributor, and which in turn 45 govern the operation of the adjusting mechanisms, different ones of which singly or in combination must be operated for the different characters to be printed.

50 We shall herein describe our invention

as applied to a printing-telegraph receiver wherein a type-wheel having several rings of type is adjusted into the positions for printing its different characters by a series of adjuster-magnets, operating singly or in combination, after the manner described in the patent of Charles L. Buckingham, No. 487,982.

In the accompanying drawings, Figure 1 is a general side elevation of a distributor constructed in accordance with our invention. 50 Fig. 2 is a general plan of the same. Fig. 3 is a sectional plan on the line $x^6 x^6$ of Fig. 1. Fig. 4 is a vertical section through the escapement and other wheels of the distributor and shows the spring connection of the same 55 with their driving shaft or wheel. Fig. 5 is a longitudinal section on the line $x^7 x^7$, Fig. 4, through the barrel containing the spring. Fig. 6 is a perspective view of one of the circuit-closer rock-shafts for the distributor. 60 Fig. 7 is a general vertical section through the receiver apparatus. Fig. 8 is an enlarged plan of the paper-feed mechanism. Fig. 9 is a rear elevation of the same. Fig. 10 is a vertical cross-section on the line $x^8 x^8$ of Fig. 9. 65 Fig. 11 is a vertical cross-section on the line $x^4 x^4$ of Fig. 9. Fig. 12 is a detail side elevation of mechanism for swinging the frame carrying the paper-feed wheel at the end of each line of printing. Fig. 13 is an enlarged 70 longitudinal vertical section through the cylinder on which the paper tube rotates and shows in elevation the paper-feed mechanism. Fig. 14 is a cross-section through the tube on the line $x^3 x^3$, Fig. 13. Fig. 15 is a section 75 through the spring connection between the driving-shaft of the feed mechanism and the motive power. Fig. 16 is a detail plan and partial section of the unison-stop for the paper-feed escapement-wheels. Fig. 17 is an 80 enlarged side view of the devices controlling the position of the axial feed-pad. Fig. 18 is a plan of mechanism that may be employed for moving the type-wheel axially. Fig. 19 illustrates the relative position of two paper 85 tubes at or about the end of the printing of a page upon one of them. Fig. 20 is a diagrammatical view of means for transmitting the positive and negative impulses suitable 90 for operating and controlling the distributor 95 100.

and the connected apparatus. Fig. 21 is a general diagram of the connections of the apparatus at the receiving end of the line.

A is the main frame in which the various parts of the distributor are mounted, and B⁵ is the driving-motor by which power is applied to the escapement of the distributor or sunflower. The motor may be an electric motor or any other driving power.

10 K² is a vertical shaft, to which B⁵ is geared through a bevel-gear, as indicated.

K' is the escapement-wheel shaft of the distributor, and 2 the escapement-wheel mounted thereon. Shaft K² carries a pinion that gears 15 with wheel 11, loose on shaft K', but frictionally connected therewith by means of a spiral spring 15, one end of which is fixed to wheel 11, while its other end rubs against the inside of a barrel 13 fixed to shaft K'. By this means 20 the driving power is frictionally connected with the actuating-wheel for the distributor and with the escapement-wheel. The latter is of any desired character so that all of the local circuits are made and broken in succession, each make and break of one taking 25 place between the similar complete operation of the circuit-controllers, which act in the circuits coming before and after it in the electric series. In other words, a complete operation 30 of the controller necessary to change the condition of each branch from normal and back to normal takes place in the one movement to the operating-wheel allowed by one movement to or fro of the controlling or escapement 35 lever. An anchor escapement is shown, a being the anchor, which is vibrated by an electro magnet or magnets C, to be presently described. The anchor is attached to the rock-shaft 16, which carries the armature or armatures S⁶ for said electromagnet.

The improved distributor herein described is especially constructed for rapid operation and for accessibility and certainty of action. To obtain rapidity of operation the cycle of 45 circuit changes which the distributor is required to produce should be repeated a comparatively large number of times in one whole revolution of the sunflower. It is found in practice that under conditions of actual use 50 a trailer, as heretofore employed, is not satisfactory for the purpose. The distributor or sunflower herein described dispenses with a trailer, gives accessibility for repair and adjustment, and admits of very rapid operation.

55 To these ends a number of rock-shafts are employed, each carrying two arms, one of which is a circuit closing and breaking arm, the other of which is the actuating-arm engaged or operated by pins or lugs on a wheel 60 carried by the shaft K'. By preference the pins are secured in the face of the escapement-wheel 2, as indicated at c. The rock-shafts (indicated at 17) are mounted in suitable bearings on the frame. At the lower end they 65 are provided with the arms 18 for engagement by the pins c. At their upper ends they carry the circuit-closing arms d. Each of the

latter is preferably made as a blade-spring projecting from a collar fastened to the shaft 17 by a screw 14 and circumferentially adjustable, whereby the relation of the circuit-closing arms to the actuating-arms below may be adjusted for the purpose of obtaining a closure of circuit at the proper time in the operation of the rocker by the lugs acting on the arms below. Contact-pins upon which the arms d close and break circuit are indicated at f, the latter being mounted in posts set in insulating-bushings in the plate 20. The pins f form, respectively, the terminals 80 or poles of circuits to be closed one at a time in rapid succession, after the manner of the ordinary sunflower circuits or branches. The arms d form the other terminals or poles, being in electrical connection with the plate 85 or frame on which they are mounted or otherwise connected to the local circuits. Retractor-springs for the rockers are indicated at 21, these being blade-springs fastened to the collars carrying the arms and being kept 90 in tension by engagement with pins or stops 22, through which the circuit of the arms is also made independently of the bearings for the rock-shafts. Back stops for the circuit-closing arms are indicated at f'. The pins c 95 engage with the beveled ends of arms 18, as shown, and in the movement of the escapement-wheel one half tooth or space consequent upon the movement of the anchor in one direction pass into and out of engagement with an arm 18, and thereby produce a make and break of circuit by one arm d. For each whole movement of the anchor to and fro a make and break of one local circuit, followed by a make and break of the 105 next local circuit in the electrical series, is produced, and on the movement of the escapewheel three whole teeth all the rockers are operated.

It will be noticed that in the same arc of 110 revolution of the distributor there is a differential number of operating pins or lugs and rocker-arms, the space between pins being less than that between the rockers and such that the rockers will be actuated in regular 115 succession by the pins in turn. The angular space between the pins is less than that between the ends of the rocker-arms and is such that in the revolution of the actuating-wheel for the angular distance covered by the pins 120 all the rockers will be operated.

In the arrangement of the pins shown in Fig. 3 the left-hand rocker-arm in the range of six at the top of the figure is supposed to be the first one operated in a cycle of six changes, 125 starting with the wheel in the position shown, and the next one to the right thereof to be the last one of the six operated. In this case the one at the extreme right would be the second in the cycle. As will be seen, the first 130 one of the cycle has a pin in position to operate it when the wheel moves a one-half tooth, while other pins of the wheel are in such position that on the successive movements of the

wheel the No. 1 rocker at the extreme right will be the next one operated, and so on, proceeding in the direction of revolution to the rocker which is the one next to the left-hand end of the range. In the arrangement shown this last or sixth rocker is the one which has just been left by the pin, and, as will be seen, is also the one which is farthest from the next pin, proceeding in the reverse direction to the direction of revolution, so that it will be the last to be operated.

It will be obvious that any rocker might be taken as the first of the cycle, the automatic unison-stop, however, being properly disposed to hold the wheel, as will be presently described, so that each cycle may begin at the same point.

Omitting for the time being the consideration of the position of the unison-stop and taking the rocker at the right as the first in the cycle, it will be seen that the wheel is about to operate upon the rocker which is last in the cycle. At the beginning of the new cycle the No. 1 rocker will be operated by its pin, while the next five pins, proceeding in the direction of revolution, are in position such that the rockers will be successively actuated, the second of them by the second pin at the next step of the wheel, and so on until finally on the sixth step the last one of the six pins would actuate the final rocker. As soon as this has taken place the next pin to the right of the one that has started this cycle of actions will have moved up into position to cause the first change of circuit in a repetition of the cycle, but the last one of the six concerned in the first cycle will not be engaged in the operation, because at the last change of circuit in said cycle it will have moved out of range of the series of rocker-arms.

As will be seen, the rockers of the series are well spaced, and the circuit-changer parts are readily accessible for inspection and adjustment, but the six changes of circuit are produced by a movement of the wheel equivalent only to the distance from one rocker-pin to the next.

On the assumption that the distributor is to be used in the system described in the prior patent of Charles L. Buckingham for controlling five local circuits by which type-wheel-adjusting devices may be operated singly or in various combinations and a sixth local circuit for restoring the devices to normal or for other purpose we have shown the distributor as provided with six circuit-changers; but it will be readily understood that the apparatus is adapted for use with a greater or less number of circuits. With an escape-wheel having forty-five teeth and an anchor-escapement it will be seen that the cycle of changes produced by the distributor will be repeated fifteen times for each whole revolution of the wheel, and if each main-line pulse produces one movement of the anchor-escapement then the revolution of the wheel will cover ninety main-line pulses. If the

distributor be used with the system of the patent before referred to, then fifteen letters or characters could be printed for each whole revolution of the shaft and wheel K' 2.

In order to obtain a powerful and extremely rapid operation of the magnet which actuates the escapement-lever for the distributor, a double winding of the core or cores of the magnet is employed, and said windings are alternately traversed by a proper current, so as to cause the said magnet or magnets to alternate in polarity. The armature or armatures are polarized. Preferably two armatures are employed, and both are actuated in both directions by simultaneously-coacting magnet-cores.

S⁶ indicates two soft-iron armatures oppositely polarized from any desired source. Preferably they are polarized by mounting them in the opposite poles of a permanent magnet S⁵. The armatures are fastened to the rock-shaft 16, which carries the anchor-escapement a.

S⁷ is an electromagnet whose core is provided with a double winding and whose opposite poles are presented, respectively, to the armatures S⁶ at one side thereof. Through these windings currents are caused to flow alternately and in rapid succession by the action of the main-line pulses; but in each coil the current flows in an opposite direction to the flow in the other, so that the cores will be reversed in polarity at each pulsation. This is conveniently accomplished by placing the two windings respectively in the two branches of the local circuit of a battery controlled, respectively, by the local contacts of relay R, as shown in Fig. 21, said relay being the main-line relay through which the pulses sent by the transmitter flow.

S⁸ is a magnet the pole ends of whose cores are presented, respectively, to the armature, but at the opposite sides from the poles of S⁷. The magnet S⁸ is also double-wound and currents are caused to flow in the windings alternately, but simultaneously with the flow of currents in the two windings of S⁷. The direction of flow in each winding of S⁸ is such that the poles of the magnet will conspire with those of S⁷, when excited at the same time, to move the armatures, the poles of one attracting said armatures and the poles of the other repelling at the same time. When the current ceases in the one set of windings and flows in the other set on the two cores, the armatures are moved in the opposite direction. The two windings of S⁸ are connected to the local similarly to those of S⁷. It is convenient to connect one of the two windings of one core into series circuit with one of the two windings in the other, but in such way that the polarities, when the current flows through the connected windings, shall conspire to move the armatures. The other two coils of the two cores are connected together in a similar way into the other branch of the local. As the armature of the relay R moves

in obedience to the reversed pulsations in the line, the armature will be caused to move correspondingly and vibrate the escapement, the latter moving in one direction for a pulsation 5 of one polarity in the main line and in the opposite direction for a pulsation of the opposite polarity. Six alternations of current on the main line will produce one cycle of changes by the distributor, since, as already 10 explained, each six vibrations of the escapement will rotate the wheel three teeth and produce the six local connections through the distributor.

The unison-stop devices, whereby the distributor may be caused to always begin its 15 cycle of changes or connections to the local circuits always at the same point in relation to the succession of main-line pulses, may be of any desired mechanical construction, but 20 are preferably controlled by a magnet provided with two coils wound differentially or reversely. Through these coils currents are caused to flow rapidly in alternation until a 25 pulse is prolonged or otherwise modified, so that a change may be effected therein sufficient to permit the operation of its armature. So long as the pulses are short and follow in rapid succession the current through each 30 coil only overcomes the effect of current through the other, and as a result the core remains unaffected. When the current is prolonged in one of them the armature is affected. This prolongation is made at the termination 35 of any number of or of every cycle or series of main-line pulses by which the distributor is moved in order to produce a cycle of changes in the local connections controlled by it. Preferably the prolonged pulse is made to follow every series of pulses by which a character or 40 letter is transmitted. There being six pulses required to produce a complete cycle of changes by the sunflower or distributor and five pulses for each letter or character transmitted, the prolonged synchronizing-pulse 45 would be the sixth pulse of a series. The unison-magnet may be polarized and will then be found to respond with great certainty and rapidity, so that no time shall be lost in making one series of pulses follow close upon another. When each letter or character is transmitted by a definite number of pulses, positive 50 and negative, the synchronizing-pulse, which is prolonged, is of always the same polarity. In practice it may be found desirable at intervals to transmit from time to time a number 55 of series of short pulses, none of which are prolonged, each series being succeeded by the prolonged pulse. The short pulses in each series may be five or more in number and insure 60 the movement of the apparatus to the unison-point. As the unison-stop is normally in position to engage, each series of pulses for a letter or character should be followed by the prolonged pulse.

65 S³ is the unison-magnet. Its two soft-iron cores are polarized from the permanent magnet S², to whose poles the cores are respect-

ively attached. Each core is wound with two coils, through which currents are made to flow alternately in rapid succession by connecting 70 said coils into the local circuits of the stops for the main relay, as indicated in the diagram, or by other means. Two coils (one on each core) are connected in series in one circuit, and the remaining two are similarly connected in the other circuit, and the coils are so wound or connected that each pulse in one set will assist the permanent magnetism and each pulse in the other will tend to cut it down. The effect of the latter upon the armature is *nil*, the retractor simply holding the armature more strongly in retracted position. The effect of the former is to momentarily increase the magnetism which would attract the armature; but the short pulses do not 85 have time to sufficiently charge the core to pull up the armature. When prolonged, however, the armature will be drawn up and remove the unison-catch (symbolized at b) from the path of the stop devices connected to the 90 sunflower. In the present case the stop is shown arranged in the path of the unison-pins, consisting of teeth upon a wheel b⁷, connected to the escapement-wheel for the distributor.

As a movement of the escapement-wheel three whole teeth produces a complete cycle of local circuit changes, the teeth upon b⁷ are made one-third in number of the teeth upon the escapement-wheel, though there might be 100 a less number of such teeth, so that, for instance, a tooth on wheel b⁷ would reach position to be locked by the unison-stop after movement of the escapement-wheel equivalent to the space of six or nine teeth of said 105 escape-wheel. The catch or stop b is mounted on an arm b¹⁰ attached to a rock-shaft b⁹, to which are secured arms b⁸ holding the armature for electromagnet S³. A blade-spring b⁶ attached to arm b¹⁰ and engaged by a tension-adjusting screw serves as a retractor for the armature-lever and to hold the catch in position to engage the unison-teeth of the wheel. If the transmission be by the perforated or embossed strip described in prior 115 Patent No. 487,982, each sixth pulse would be prolonged to make a synchronizing-pulse, as indicated in Fig. 20 of the drawings, and allow the wheel to pass the unison-point to begin the new cycle. At intervals a series of short 120 pulses, preferably limited in number to the number in a letter or character transmission followed by the long pulse, could be used from time to time to insure synchronism, as indicated at the end of the section of perforated 125 strip. The prolonged pulse would in each case be that which causes the receiver to put an impulse through that one of the differential coils on S³ that strengthens the magnetism thereof, thereby withdrawing the stop b simultaneously with the movement of the escapement, which allows the wheel to move and carry the stop-tooth past the tooth. The 130 next pulse at the beginning of the next series

allows the armature to fall back and the tooth to move in toward the wheel in position to catch the next unison-tooth, which, however, it is prevented from doing by the final prolonged pulse of proper polarity ending up such series as the tooth gets around to position to engage the catch. The prolonged or sixth pulse following the transmission of each character, besides operating on the synchronizing-magnet, affords also a slightly-prolonged space or interval of time in which the operation of the paper feeding and printing devices and the dogging-magnet and the resetting of the armatures for the selecting-relays or of other devices which are instrumental in setting the type-wheel to position for printing a character may be effected.

In the diagram Fig. 21 is the controlling-magnet for the several selecting-relays U V W X Y, whose circuits are consecutively closed by the distributor. This magnet is preferably a double-wound magnet and the circuit of its two coils are closed alternately and in rapid succession by the action of the relay R, which is operated by the main-line pulses. For each main-line pulse a current is caused to flow through one of the coils of magnet S. On the prolongation or strengthening of an impulse through one or the other of said coils the said magnet S becomes excited, so as to operate its armature and close the circuit of the selecting-relay whose circuit is at such time closed at the distributor. If the pulses are short and follow each other in rapid succession the current through one coil only overcomes the effect of a current through the other, and as a result the core remains insufficiently magnetized. When, however, the current in either coil is prolonged its effect will quickly overcome the effect of magnetism due to the other coil, and as a result the relay is brought into action.

The controller-magnet S has its two coils included, respectively, in series circuit with the two coils of the unison-magnet S³ and with the two coils of the electromagnet which operates the escapement of the distributor, all these said magnets being thus included in practically the same local circuit controlled from the two contacts forming, respectively, the front and back contacts of the main-line relay R. These several magnets may be thus operated all in the same local circuit without confusion, each performing the duty required of it exactly.

The selecting-relays U V W X Y control the circuits of adjuster-magnets 1^a 2^a 3^a 4^a 5^a, which latter operate upon adjuster-levers and mechanisms conveniently termed "followers," which are mechanically connected with the type-wheel and serve to rotate and move the same axially for the purpose of adjusting it to different positions according to the particular adjuster-magnet or combination of adjuster-magnets brought into action in any one cycle of changes produced by the distributor. The selecting-relays are connected into

the local circuits through the contacts f of the distributor in the order indicated.

The order of connection and operation is such that the adjuster-magnet whose follower has the greatest distance to move shall be brought into action first in the cycle of changes produced by the distributor, and so on in regular order, that adjuster-magnet whose armature has to move the least distance being controlled by the selector-relay connected to contact No. 5, which is the last one of the contacts for the distributor over which circuit is closed in any cycle excepting the final contact 6. The latter is the one which may be employed for closing a restoring-circuit 98 99, that is closed at the termination of each cycle of operations for the purpose of restoring the armature-levers of the selecting-relays to normal position. The current on this restoring-circuit does its work through another set of coils on said relays, as described in the patent of Charles L. Buckingham, No. 487,982.

The press-magnet c' is operated once for each cycle of changes corresponding to that by which a character or letter of the type-wheel is set into position. Preferably this action is produced by a circuit-controller connected to the distributor itself, as described in application of Charles L. Buckingham, Serial No. 507,673. The closure of the circuit for the press-magnet might take place at any stage of the cycle of changes produced by the distributor; but the particular point in the operation of the distributor where this circuit is closed would be determined by the time required to bring the pad against the paper after the closure of circuit. This would of course depend, among other things, upon the sluggishness of the press-magnet. In any case the time of closure should be such that the press will do its work just before the resetting devices come into action to move the type-wheel back to the zero position.

In practice the controlling-circuit for the press-magnet might be closed at the end of the fourth or the beginning of the fifth change of circuit produced thereby, the said fifth change being that which corresponds to the adjusting mechanism which has the least distance to move and is always the last to be brought into operation on any cycle of actions. If the circuit of the press be closed even on the fourth, the delay in the operation of the press may in some cases be found sufficient to allow the adjustment of the type-wheel corresponding to the fifth closure of circuit to take place before the press will reach the paper; but if the action of the press be quick the closure of its circuit might be coincident with the fifth change. By preference, however, we control the press-magnet coincidently with the sixth change of circuit produced by the distributor, so that the action of the adjusting devices will certainly precede that of the press-magnet and the press cannot at any time strike the paper until all

the adjustments of the type-wheel have been made. The controlling-circuit for the press is conveniently closed by one of the actuating-pins of the distributor, which is made to operate on a circuit-closer composed of a rock-shaft having circuit-closing and actuating arms similar to those already described. The actuating-arm for this shaft is indicated at 18' and the circuit-closing arm at d²⁰. The actuating-arm is shown in position to be operated by a pin at or about the fifth change of circuit in each cycle of changes produced by the distributor, but might obviously be, and preferably is, arranged to operate coincidentally with the sixth change.

The circuit of the press-magnet may be closed directly by the distributor mechanism; but, as ordinarily the press-magnet requires a rather heavy current, it may be found desirable to interpose a relay between the circuit-controller and the press-magnet, the latter being in such case operated from a second local closed by the relay.

The type-wheel W', to the control of which the distributor just described may be applied, is preferably constructed with a number of rings of type, as described in prior patent of Charles L. Buckingham, No. 487,981, and may be adjusted circumferentially and axially to the different positions required for printing its characters by means of various impelling devices brought into operation successively or simultaneously in proper combinations, as described in that patent and in Patent No. 487,982. By the axial movement any desired ring of type is brought into line with the press-pad, and by the circumferential movement any desired type of that line is brought to position. By these movements, singly or in combination, any type of the several rings may be brought into position.

F G II I J, Fig. 7, are adjuster levers or arms operated by connection with the armatures 12 of corresponding adjuster-magnets 45 or pairs of magnets numbered 1^a 1^b 2^a 2^b 3^a 3^b 4^a 4^b 5^a 5^b, Fig. 21. These arms operate upon drivers and followers of any proper construction, as described in those patents, some to rotate the wheel and others to move it axially. The means herein shown for rotating the wheel are substantially those of Patent No. 487,981, but those for procuring the axial movement are somewhat modified, being simplified, particularly in their manner of operation upon the type-wheel shaft.

w' w² w³ are the axially-moving drivers upon which the arms F G H operate to rotate the type-wheel to different positions circumferentially, while i i² i⁴ are the corresponding followers with which the drivers engage. Each of the drivers is provided, as shown, with a collar having a groove, within which project pins extending from prongs of the impelling-levers F G H, thereby allowing 65 rotation of each driver under the action of other impelling devices. Each follower i i² i⁴ is provided with a spiral slot, into which takes

a pin of the corresponding driver w' w² w³, so that when the driver is moved axially by the impelling-lever the follower will be compelled to rotate and thereby rotate the type-wheel. Each follower is held from endwise motion in a pawl-bearing, in which it is adapted to rotate freely. Each driver w² w³ is provided, as shown, with a pin which takes into a straight slot in the follower to the rear, whereby the driver may be moved axially without rotating the follower to the rear, while if the follower to the rear be rotated the driver ahead will be compelled to rotate with it. 70 The extreme driver w' to the right has a pin which takes into a straight slot in the fixed bearing, and by which it is thereby held from rotation when actuated axially by its impelling-lever. The extreme follower i⁴ to the left 85 is connected with the type-wheel shaft, or extension thereof, by a straight slot and pin, as shown, whereby the type-wheel will be compelled to rotate with the follower i⁴, but may be nevertheless itself moved axially by devices to be presently described for the purpose of presenting different rings of type to the impression-pad. By preference the spiral slots in the followers upon which the impelling-levers F G operate are cut in one direction and reversely to the spiral slots in the follower i⁴, upon which impelling-lever II operates, so that F and G will move the type-wheel in one direction of rotation from position of rest, and II will move it in the other 90 direction in case any one of said levers be moved by itself. As explained in the Patents Nos. 487,981 and 487,982, above referred to, it is by this means rendered unnecessary to rotate the wheel more than half-way in either 95 direction to bring any type into position for printing.

By a combination of the movements of the levers the type-wheel may be caused to take any one of the positions required for printing 100 from any particular type of a ring. The follower i⁴ is adapted to turn the type-wheel one-half a revolution and under the impulse of the impelling-lever II, while the followers i² and i turn the wheel in the opposite direction, 105 respectively, one-quarter and one-eighth of a revolution. This proportion and combination of followers provides for bringing any one of eight types in a ring to position for printing and by a revolution of the wheel in no case 110 more than one-half from the normal position of rest.

The impelling or adjusting levers I J operate upon mechanism which serves to adjust the type-wheel axially to positions for printing 115 from different rings of type-wheel. When both are at rest in normal position the ring next to the right-hand side of the type-wheel, Fig. 6, can be printed from. When lever I operates, the wheel is moved axially to the left to bring 120 the next or extreme right-hand ring into position opposite the press-pad. Lever J operating alone moves the wheel the axial space of two rings to the right to bring the extreme

left-hand ring into position, while if lever I be operated at the same time the wheel will be adjusted axially backward from position to print from the extreme left-hand ring, so as to bring the next ring or left of the two inner rings into position, which latter is the position shown in the figure. As will be understood, these axial adjustments may take place simultaneously with the operations of turning the wheel by the followers at the other end of the shaft or may take place while said followers are stationary. For producing these different adjusted positions of the wheel axially by the action of the levers, singly or in combination, any means—such, for instance, as those described in the prior patents herein referred to—may be employed. We prefer, however, to employ the following simplified means devised by us, which insure certainty and rapidity of action, but which we do not claim herein, as they form the subject of another application for patent filed by us May 20, 1895, Serial No. 549,861, wherein we have set forth the use of the device for producing, not only the axial, but the circumferential adjustment also. The distinguishing feature of this device is an arm or lever both ends of which are movable singly or together under the action of the two impelling devices, respectively, and each around the other as a fulcrum, while said arm or lever is itself connected to the axially-movable wheel.

42, Fig. 18, is the lever, and 43 44 the two fulcrums formed by the pivotal connections of the links 45 46 with said lever. Through the latter the adjusting or impelling devices I J operate upon the lever 42, I being connected to a lever 47, to which 46 is joined, and J to a lever 48, to which I is joined.

40 The type-wheel axis is connected to 42 by a short rod or piece 51, which is pinned at one end to the lever 42 and at the other connected to the shaft or axis in such way as not to interfere with the free rotation thereof, while 45 at the same time being adapted to move it positively backward and forward. For this purpose the piece 51 is turned down, so that it may pass through the end of a bushing tapped into the hollow end of the type-wheel axis, and within the end has a head fastened to it, as shown in Fig. 23, the whole forming a simple coupling adapted to the purpose stated. Adjuster I turns the end 43 of lever 42 about 44 as a fulcrum, so as to move the shaft the space of one ring of type in the direction of the arrow 49. Adjuster J moves the end 44 of lever 42 about 43 as a fulcrum a distance sufficient to adjust the axis in the direction of the arrow 50 two rings of type, in 50 an obvious manner. When both adjusters operate, the end 44 moves about 43 as a fulcrum a distance sufficient to carry the type axially two rings of type in the direction of arrow 49; but the end 43 is at the same time moved 55 about 44 as a fulcrum, so as to carry the point of attachment of the type-wheel shaft backward in the direction of arrow 50 axially the

space of one ring, and the resultant of the action is the movement of the type-wheel in the direction of arrow 49 one ring. As will be seen, the wheel may be thus moved from the normal position, in which the second ring from the right, Fig. 6, is in position to print, into position to bring either of the three other rings into position over the pad. If the ring at the extreme right or left were normally in position, it would obviously be necessary to give the wheel an extreme axial movement over three rings, and the movement of both ends of the lever 42, acting singly, would in that case have to be in the same direction, whereas in the arrangement shown the two ends move in opposite directions and the greatest extent of movement required is over the space of two rings. The forward motion of each arm F G H I J is produced by the electromagnets 1^a 2^a 3^a, &c. Its backward or return movement is produced by the electromagnets 1^b 2^b 3^b, &c., which take the place of retracting-springs by acting upon the armatures in the opposite direction to magnets 1^a 2^a 3^a and are energized at the end of the transmission of each character. These magnets 1^b 2^b, &c., insure by a positive action the restoration of the impelling devices and type-wheel to normal position. By so controlling their circuits that they shall be cut out of action when the magnets 1^a 2^a, &c., are cut in, and vice versa, the adjuster-magnets are relieved of the work of overcoming the retractor-springs heretofore employed and a much more rapid and satisfactory operation of the adjuster mechanism may be obtained. This control of the restoring adjuster-magnets is well attained by placing them in local circuits from the back contacts of selector-magnets, which at their front contacts close the circuits of the adjuster or actuating magnets 1^a 2^a 3^a, &c. In the normal position of the selector relay levers the circuits of magnets 1^b 2^b, &c., are closed and of 1^a 2^a, &c., are open. When any selector-relay is operated the armature breaks circuit of 1^b and closes circuit of 1^a or 2^a, thus moving the corresponding adjuster mechanism. When the selector magnet or relay returns to normal position by the closure in any proper manner of a restoring-circuit including coils upon it, then the local of 1^a is opened and of 1^b is closed. The paper upon which the printing is done may be supported and fed as follows: C' is a tubular support of brass or other suitable material having a smooth exterior surface. This tube serves as a support for a tubular blank, upon which the lines are printed circumferentially around the said blank, the blank being fed or moved circumferentially and axially for the purpose. The blank itself is a sheet formed into a paper tube by cementing the edges together by any suitable means. The formed tube is slid endwise upon the supporting-tube C'. The latter, as shown in Fig. 19, is preferably of such length as to support two paper tubes at the same time, one of

such tubes being that upon which the printing is being done, while the other is arranged in close proximity thereto, so as to be capable of being slipped quickly into position when 5 or about when the first paper tube is filled.

In the drawing Fig. 19 two tubes are indicated, that one at the right being the one upon which the characters are being printed and that at the left the one which is in position to slide beneath the type-wheel as soon as the last line on the first one has been printed. The end of the supporting-tube is made slightly conical, as shown, to aid in the ready application of the formed paper tube. 15 Sufficient space should be left at the right-hand end of the tube C', from which end it is supported, to permit the blank when printed to be quickly slipped to one side and a fresh blank to take its place. After the 20 latter has been moved into position for printing the first is removed from the tube by opening it on the line where the edges of the sheet are joined. The second is then fed along over the tube in the same manner from 25 left to right, Fig. 19, this being the axial movement of the paper tube corresponding to the feed which is necessary to make the vertical space between lines on the printed page. The press-pad p' works through an 30 opening in the supporting-tube C' beneath the type-wheel W'. This pad is supported on the long arm of a bell-crank lever which is pivoted on a bracket or frame c', fastened within the supporting-tube C', and has its 35 short arm connected with the armature-lever c⁹ of the press-magnet c' by a rod or wire c¹⁰, extending outside the tube C' through the end thereof at which it is supported on the frame of the apparatus. The magnet is operated in any suitable manner as soon as the 40 letter is brought into position for printing, but by preference through the action of a circuit-controller, which causes said magnet to be energized once for each cycle of changes 45 produced by a sunflower or distributor that governs the operation of the adjusting devices by which the type-wheel is fed into the desired positions, and as will be described farther on. The press-lever is retracted by a 50 spring c⁸, applied directly thereto instead of to the armature-lever. The press-magnet is mounted on a pivoted frame c⁵, provided with adjusting-screws c⁶, whereby the 55 positions of the magnet may be changed to take up slack in the wire c¹⁰ and adjust the throw of the press-lever. The armature of the press-magnet is also provided with a suitable contact-spring 73, whereby when the magnet is not energized it may close the circuit of a 60 contact-post 74, and when the magnet is energized to operate the press it will break said circuit.

In the normal position of the press the circuit by spring 73 is closed. This circuit, as 65 will be presently described, includes the escapement-controlling magnet for the paper-feed devices, which are preferably so organ-

ized that the feed will be allowed upon a movement of the escapement devices due to the excitation of said controlling-magnet, but 70 not by a movement of the armature thereof which is produced by breaking the circuit of said magnet at the contact 73.

To produce the circumferential feed of the paper tube, it is preferable to employ a friction device directly engaging with the paper tube. This device is also by preference a wheel, which remains in engagement with the paper during the printing of a line and is turned intermittently to produce the letter 80 and word spaces.

The axial feed is produced by a device which is normally disengaged and is brought into operative engagement at the end of a line and before the beginning of the next 85 line, the circumferential-feed device being automatically withdrawn during such axial-feed operation. The axial-feed device also by preference engages directly with the paper and consists of a friction-pad made to 90 reciprocate after the manner of a pawl and in a line parallel to the axis of the paper tube.

B is the circumferential feed-wheel mounted on a shaft d' whose bearings are in any suitable support adapted to withdraw the feed-wheel from engagement with the paper. This support is herein shown as consisting of the rocking frame E, which, for convenience, is made to rock on the shaft d² of a gear-wheel D³ in the train of wheels between the feed-wheel B and the devices by which its intermittent motion is produced. To insure the proper feeding of the paper tube an idler friction-wheel B⁶ may be mounted within the tubular support C', with its edge arranged to 105 rotate in an opening in said tube opposite feed-wheel B. The paper is grasped between the wheels B and B⁶. A spring d⁹ connected to a cross-bar at the rear of frame E causes the feed-wheel to grasp the paper tube with 110 a yielding pressure. By adjusting the tension-spring, and thus varying the pressure the extent of feed at each of the intermittent movements of the wheel may be varied. With a lighter pressure a longer feed will be produced, and vice versa. A means of adjustment is afforded by a set-screw d⁸, bearing 115 against one arm of an elbow-lever d', the other arm of which is connected to the spring d⁹, as shown in Fig. 13.

D is a wheel fixed to the main or driving shaft G' of the apparatus and gearing with a wheel D², which in turn gears with wheel D³. The latter wheel gears with the pinion d³ on the shaft carrying the feed-wheel B. 125 The main shaft G' being governed in its movement by a feed escapement device secured to it, the desired movement of the paper is obtained both for feeding from letter to letter and from word to word, as well as from the 130 end of one line to the beginning of the next. The escapement devices, which are constructed to produce or allow an enlarged or amplified feed movement of the feed-wheel au-

tomatically at the end of a line, thereby covering the margin of the page both at the end and beginning.

The main driving-shaft G' for the paper-feed devices receives motion from any suitable motive power, as, for instance, an electric motor driving a shaft (indicated at T) which carries a bevel gear-wheel t , meshing with a gear t' , that is loose upon the main shaft G' . The wheel D , which transmits motion to the feed-wheel that rotates the paper tube, is keyed to said shaft and carries or is fastened to a barrel t^2 , containing a spiral spring t^3 . One end of said spring is fastened to the barrel t^2 and the other end to the hub of the bevel gear-wheel t' . The motive device which turns the shaft T keeps the spring t^3 under tension, its power being adjusted, however, to that of the spring, so that it shall not wind the spring tightly, but when the spring has acquired a certain tension the power of the spring is sufficient to prevent further movement of the motor. The power stored up in the spring keeps shaft G' under constant or practically constant tension, irrespective of any irregularities of movement in the driving-motor, and also produces a quick or prompt movement thereof when it is released by the action of the escapement devices. By this means an electric motor can be used to supply the power for driving the apparatus and the difficulty which would arise from the inertia of the motor in stopping and starting, if connected directly to the shaft G' , can be avoided. A pawl may be applied to any part of the mechanism between the spring and motor to prevent the latter from running down when current is shut off from the motor. The shaft G' carries or is connected to an escapement-wheel that is released step by step to produce the step-by-step feed of the paper tube through the wheel D and the intermediate gear. It is so constructed as to permit an enlarged or amplified feed movement of the wheels when the end of a line is reached. The main shaft G' carries also a cam g , that operates upon or controls the devices for giving an axial feed to the paper, as will be presently described.

As an example of a feed-controlling escapement which may be employed for producing a step-by-step feed of the paper tube circumferentially and an enlarged or amplified feed at the end of a line an escapement of the same general character as that described in an application of Charles L. Buckingham, filed April 16, 1894, Serial No. 507,673, has been shown.

An anchor-escapement lever u , Fig. 10, is vibrated by the operation of a magnet h , whose armature is secured to said lever, the lever being provided with a suitable retracting-spring u^6 or other suitable device, as shown. The anchor-escapement has two pallets, engaging, respectively, with escapement-wheels indicated at r^2 r^3 . These wheels are connected with the shaft G' , so as to be rotated

by the power of the spring t^3 when the teeth are released by the pallets of the anchor.

Owing to the peculiar construction of the escapement devices two toothed escapement-wheels r^2 r^3 are employed. One pallet u^1 of the anchor engages with the teeth of wheel r^3 and the other pallet u^2 engages with the teeth of the wheel r^2 . The latter pallet is movable on the arm of the anchor by which it is carried. For this purpose it is properly pivoted at u^3 on one prong of the lever u . Against the tail of the pallet bears a spring u^5 , the office of which is to move the toe of the pallet backward in a direction opposite to that in which the escapement-wheel rotates, so as to clear the tooth with which it was last engaged when it comes forward to be engaged by the next tooth of the wheel. A stop u^4 limits the movement of the pallet when it is engaged with the wheel and the latter is permitted to rotate through disengagement of the pallet u^1 . At 23 is a back stop for the pallet u^2 .

In order to provide the amplified or enlarged feed at the end of a line whereby the paper may be fed circumferentially to the beginning of the next line, a blank space q is provided in the wheel r^2 . The effect of this, as will be seen from the explanation presently to be given, is that when the pallet u^2 has been disengaged from the tooth at the forward end of the space q and by the action of the magnet is moved into said space the wheel, which is at the same time by such movement released, may turn until the tooth at the rear end of the space q engages the toe of the pallet and is stopped thereby. This enlarged or amplified feed-space is adjusted to be sufficient to cover the space or margin (proceeding in the direction of the ordinary feed) from the end of one line circumferentially to the beginning of the next line, the proper vertical space-feed being produced in any proper way. Normally the lever u stands in position to hold the pallet u^2 in engagement with a tooth of the wheel r^2 , being held in such position by the attraction of the magnet h . The pallet u^1 is disengaged. Simultaneously with the operation of the press-pad the circuit of the magnet h is broken and the anchor u is thereby allowed to move backward, in which movement it brings the pallet u^1 into the space between the teeth of the wheel r^3 and in such position as to allow no or very little movement thereof when the pallet u^2 leaves the teeth of the wheel r^2 with which it is engaged. In this movement the pallet u^1 engages before the pallet u^2 is disengaged. At the instant the pallet u^2 is freed from its tooth the spring, acting thereon, moves its point slightly in the arc of a circle around its pivot to such distance that when the lever u moves forward again under the action of the magnet the point of the pallet instead of moving into position to stop the tooth with which it was last engaged will come

into position to catch the next tooth as soon as the wheels are freed by the movement of the pallet u' . As will be seen, therefore, the backward movement of lever u allows no movement of the wheels; but on the forward movement thereof the wheels are freed by the pallet u' and allowed to rotate a small distance until again locked by the pallet u^2 . This latter movement is confined by the stops for the pivoted pallet u^2 , and in this movement a proper feed of the paper is allowed to take place. The magnet h retains the parts in this position until the next operation of the press, when the action is repeated. It will be understood that the first action of the press is to discharge the magnet h and allow the lever u to recede; but in this action no feed of the paper takes place. The instant, however, the impression has been effected and the press is restored or makes its backward stroke then the magnet h is excited and a release of the wheels takes place to produce the feed of the paper. The action of the devices is, therefore, to allow the feed to take place on one movement only of the vibrating armature-lever and yet to secure a positive control of the escapement-wheel.

The action of the magnet may be controlled by any suitable devices or arrangements of circuits, one of which will be hereinafter described and is indicated in the diagram. When the wheels have rotated to bring the blank space q around opposite pallet u^2 , then the amount of movement will be greatly increased when the magnet h allows the wheels to rotate, the amount being then that of the blank space q plus the amount of movement allowed after the edge of the tooth at the right of the space has engaged the yielding pallet u^2 , as already explained. This position is the zero position or position for beginning a new line of printing on the paper tube. The magnet h is preferably excited on each back movement of the armature-lever for the press-magnet c' , said armature-lever controlling through its back stop 74 the circuit of magnet h , as clearly shown in the diagram Fig. 21. At each such excitation the escapement-wheels move one tooth, and a corresponding movement of the paper tube circumferentially on the support is produced. The gears are so proportioned that the large blank space on the escapement-wheel shall be reached once for each whole revolution of the paper tube, and the tube then moves a long feed-step to cover the margin between the end of one line of printing and the beginning of the next line. At the completion of the movement across the edge of the paper sheet the feed-wheel B is automatically withdrawn from engagement with the paper by the following devices, timed to operate in the proper manner upon the support E for said feed-wheel, and the axial feed device then operates.

E^2 is a rocker-frame swung on the main shaft G' or other suitable support and hav-

ing on one of its arms a segmental gear e , which engages with a similar segmental gear e' on an arm of the rocker E . Secured to the rocker E^2 , but on the opposite side of its center of swing, is a hook E^3 , pivoted on the side of the frame and having a toe e^3 in position to be engaged by a lifter E^4 , connected with the escapement-wheel or other portion of the mechanism and timed to engage the hook and lift it, together with the end of the rocker to which it is secured, at the conclusion of the movement of the escapement feed device by the amplified or enlarged feed already referred to. The effect of lifting the hook, as described, will obviously be to depress the feed-wheel B , thus disengaging it from the paper tube and leaving the latter free to be moved axially the adjusted vertical space between lines on the printed page, immediately after which the hook E^3 is released and the parts permitted to return to normal position and bring the wheel B again into engagement with the paper. The lifter E^4 is conveniently clamped upon the main shaft G' or other shaft which carries the feed-escapement, as shown in Fig. 12, and its time of engagement with the hook may be adjusted by loosening the clamping devices and setting the lifter at any desired position circumferentially on said shaft. The prompt disengagement of the lifter and hook is insured by means of a pin e^4 on a fixed portion of the framework and with which the tail of the hook engages to release the hook just previous to the time when the escapement devices reach the zero-point and the desired axial feed has been produced.

To insure the stoppage of the paper tube always at the same point after the enlarged or amplified feed, so that the new line shall always begin at the same distance from the margin, a suitable locking device is employed to automatically lock the feed-wheel at the end of the required amplified or enlarged feed movement. This locking obviously must take place once for each whole revolution of the tube and of the escapement-wheels and should be made to occur at or just before the lifter engages with the devices by which the paper-feed wheel is itself moved away from engagement with the paper. The paper-feed wheel being thus positively stopped while engaged with the paper, the latter will always stop at absolutely the same point, which it might not otherwise do if the paper-feed wheel were moved away from it while the said wheel is rotating. Under such circumstances the slight momentum acquired by the paper tube might carry it beyond the proper position which it must have in order that each line may begin at exactly the same distance from the margin.

The cessation of rotary movement of the feed-wheel is provided for by a lost movement in the train of gear between the wheels D and D^2 at each whole revolution, the gear-wheels D and D^2 being for this purpose pro-

vided with a blank space, which allows movement of the wheel D practically one tooth without moving wheel D². During this lost movement the wheel D², and consequently feed-wheel B, are positively locked from movement.

The blank on wheel D is indicated at 30, and that on D² at 31, Fig. 11. Wheel D² is in two parts, one part of which has the blank space, while in the other part where it engages with wheel D³ there is an unbroken line of teeth around its whole periphery. The blank 30 is formed on the arc of a circle whose center is the axis of rotation of the wheel D, while the blank 31 describes practically the same arc, but forms a depression in wheel D², so that when the two blanks come to coincidence the wheel D may turn a short space without imparting motion to wheel D², but the latter will also be positively locked from movement by the interlocking of the wheels at the blank space. As soon as the wheel D has moved the space of one tooth, more or less, with its part 30 engaged with 31, a new tooth on D will engage with a tooth on wheel D² and the movement will be taken up again. This blank, or lost space, is near the end of the blank in the escapement devices, so that the feed-wheel will be brought to rest after the proper circumferential feed has been produced. When this point is reached, but not until then, the operation of withdrawing the feed-wheel B will take place through the operation of the lifter. Just as soon as it is withdrawn it may be allowed to begin to rotate again under the operation of the driving mechanism while the latter is producing the axial feed. It should be understood that the wheels D and D² have the same number of teeth; but the pitch of the teeth on D is smaller than on D², so that D may always leave and take up D² at the same point.

While for the sake of convenience and simplicity the means for locking or positively stopping the feed-wheel just prior to its disengagement from the paper are made a part of the gear by which power is applied to turn the wheel, it will be readily understood that the said means might be otherwise constructed or applied without departing from the invention, it being only necessary that they should be timed to come into action as described, so as to positively stop the paper before and at the instant it is freed from the control of the feed-wheel.

When the feed-roll is mounted and connected with the driving-train, as shown, the torque of the wheel D³, which gears with the wheel d³, mounted on the rocker-frame carrying the feed-roll, is exerted upon the frame in a direction to tend to lift and hold the roll against the paper. This we find in practice to be very desirable, for when the torque is in a direction to depress the wheel the feeding action is irregular and uncertain, even though a spring of considerable tension be applied to the rocker to hold the wheel up.

The axial feed device operates by frictional engagement with the paper tube, and is composed preferably of a pad of soft rubber B² or other suitable material—such as cork—mounted on an arm of lever B³, which in turn is carried by lever B⁴ or other suitable reciprocatory support. The support B⁴ is engaged at its upper end by the cam g on the main shaft G' or other suitable shaft and is moved by said cam in a direction to take a fresh hold upon the paper. When the feed of the paper is to take place, the cam releases the lever, and the latter, under the influence of a spring in which power has been stored by the action of said cam in moving the lever backward, now moves forward and feeds the paper by the action of the pad B², which has been brought up into engagement with the paper automatically through devices connecting with or timed to operate with those by which the feed-wheel B has been lowered. The spring 25, which actuates the support B⁴, may be applied thereto in any desired way. It is here shown as connected to one arm of the lever which carries the feed-pad, and in such manner as to tend to lift the pad up to engage with the paper. The spring indicated at 25 is fastened at one end to the frame and at the other to the arm of lever B³, Fig. 13.

As will be obvious, the movement of the lever B⁴ to the left will put the spring under additional strain. In order to insure a cessation of this rearward movement of the lever and pad before the feed-pad B² is permitted by proper devices to engage the paper, the end of the cam g, just before the releasing-shoulder is reached, is made straight, as shown at 27, Fig. 8.

The movement of the axial feed-pad upward into engagement with the paper is controlled by means of a connection of lever B³ with one or the other of the rockers in such way that when the latter are operated to lower wheel B the spring 25 will be permitted to swing the lever B³ and raise the pad. The latter will, as is apparent, describe an upward and backward movement, thereby causing it to wedge itself slightly on the paper and so as to have a good grip when the lever B⁴ is released by the cam. The connection of the lever B³ and a rocker is shown as consisting of a yoke 28, fastened to the lever, and a link or hanger 29, carried by an arm of rocker E² and vertically adjustable thereon, as indicated in Fig. 17. When the latter is operated by the lifter on shaft G', the left-hand end of lever B³ is permitted to drop under the action of the spring which lifts the pad. Normally the left-hand end of B³ is held up by the rocker, which is provided with a proper spring or retractor d⁹, as already explained, which restores it to normal position when the lifter leaves hook E³. The connection of the axial feed pad or pawl with the devices which lower it are, as seen, such as not to interfere with the backward movement of the feed device preparatory to moving the paper another

step or with its movement forward to feed the paper.

The general operation of the paper-feed devices thus far described is as follows: After each impression of a letter or character by the press-pad the escapement-magnet h allows the escape-wheels to rotate one step, thereby permitting the shaft G' and wheel D to move and to move the circumferential per-feed wheel B the required distance between letters. At the termination of each word it may be moved one or more spaces by repeating the operation of the press-pad on the blank of the type-wheel. This movement is repeated during the printing of the line, during which operation the axial feed-pad remains out of engagement with the paper, being held there owing to the fact that the rockers are held in position by the action of their retractors, with the right-hand end of the lever B^3 , carrying the axial feed-pad raised, its opposite end being thereby depressed. The same retractor by holding the end of the rocker E down lifts the inner end and holds the paper-feed wheel B against the paper. As soon as the escapement devices reach the amplified feed or blank space in the escape-wheels, the extent of which blank space is determined by the total margin to be covered at both edges of the page, the shaft G' is permitted to move the required distance without interference from the escape-wheel, which movement takes place in a very short instant of time, as the shaft G' is under the stress of the spring t^3 . This movement quickly turns the wheel D , and with it the feed-wheel B , a long space. At the beginning of this movement there is no change in the relative position of the other parts of the mechanism and the feed-wheel continues its movement, rotating the paper tube past the end of one line and across the margin between the edge of the paper and the beginning of the next line on the page. At this point the blank space in the gear-wheels D D^2 is reached, positively locking the feed-wheel from further movement, although the shaft G' is free to continue its movement. This point of locking is reached shortly before the blank space or enlarged feed-space q in the escapement-wheel is covered, thereby permitting a slight further movement of the shaft G' for the completion of the operation of feeding the paper before a new line is begun. The feed-wheel being thus positively brought to a stop the lifter E^4 , coincidently with said stoppage, or immediately thereafter, takes against the hook E^3 , thereby operating the rockers and moving the feed-wheel B from engagement with the paper, while at the same time permitting the spring 25 to turn the lever or arm B^3 on which the feed-pad is mounted, thereby moving said pad upward and slightly backward to engagement with the paper. This movement of the two feed devices takes place in the slight movement of the shaft G' permitted before the end of the blank space on the escape-wheels is reached. As soon as the

axial paper-feed B^2 is engaged the lever B^4 escapes from the cam and the axial feed is produced. During the movement of the rockers the shaft G' is revolving and the hook on the rocker is engaged and continues in engagement until the hook is dropped by the tail of its lever engaging with the pin on its frame. As soon as this has taken place and practically coincidently with it the escape-wheel will have reached the zero position or point of rest at the end of the enlarged or blank space q thereon and ready for the beginning of a new line. The passage of the actuating-arm by the hook on the rockers allows the latter to return to normal position, thereby bringing the paper-feed wheel into engagement with the paper and lifting the right-hand end of the lever B^3 , so as to withdraw the axial feed device from engagement, the same having now completed the axial feed. The revolution of the shaft G' now begins in the printing of a new line, and the cam g in its revolution moves the lever B^4 back to position for producing another axial feed movement after completion of the line. The tube C' is provided with a proper index-mark, with which the joined edges of the paper sheet formed into the tube should coincide when the paper tube is slipped upon the tube C' , in order that the printing of the line may begin at the proper distance from the margin of the page. In order to allow a new paper tube to be instantly slipped under the type-wheel when or about when the end of the last line of a tube is reached, we provide means for withdrawing the feed-wheel B from engagement with the paper and at the same time holding down the axial feed-pad away from engagement with the paper. This may be done by the operation of a single slide-rod or manually-operated device under the control of the operator and which governs both paper-feed mechanisms at the same time in the manner described. Coincidently or practically coincidently with the manipulation of said manual device the fresh tube is moved axially upon the tube C' into position beneath the type-wheel, the tube previously printed upon being by such movement slipped to one side. There is also provided a suitable mechanism also actuated or controlled by the same manual controlling devices for disengaging the escapement-wheel for the paper-feed devices from the escapement-pallets, thereby permitting said wheel to run freely under the action of the motive power to the zero or starting position, so that the printing on the new page may begin at the proper marginal distance from the edge next the beginning of lines. This additional device for freeing the escapement-wheels is rendered necessary by the fact that in the rapid operation of the apparatus when used as a telegraph-receiver it is impossible for the operator to time the action of slipping a fresh tube into position with the arrival of the escapement devices at the blank space or space for producing the enlarged feed.

By, however, freeing the said wheel from the escapement device at any point and by the provision of an additional automatic stop properly located to come into action when the 5 wheel is thus freed from the escapement the apparatus may be caused to begin upon the new page always at the same point.

Apparatus constructed in detail as will be now described may be used for these operations. *M* is a suitable actuating slide rod or bar provided with an operating-handle, and *n* is an arm attached to said bar and engaging by means of a fork with the hub of the escapement-wheels *r² r³*, said hub being provided with a circumferential slot, with which the ends of the fork engage, whereby the wheels may at all times revolve freely, but may by means of the said slide-rod be moved axially on their driving-shaft. To permit them to be so moved the said wheels are connected with the said shaft *G'* by a spline or feather connection, whereby they are rotated positively by said shaft, but may slide longitudinally thereon. A check-spring *45* may be provided to hold the actuating-slide in normal position, so as to prevent accidental sideways movement of the escapement-wheels. The check-spring *45* is secured at one end to the frame and at the other end is provided 30 with a dog entering the groove or notch in the side of the slide-rod. A forcible application of power to the slide-rod, however, disengages the spring. When the escape-wheels are moved to one side they are, as will be obvious, disengaged from the escapement-pallets which control the movement of said wheels, and said wheels might therefore revolve freely under the action of driving power for shaft *G'*. Their movement of rotation, 35 however, when thus freed is controlled by an automatic zero-stop, (indicated at *55*, Fig. 16,) which is arranged in position to be engaged by a pin *56* on the side of the escape-wheels when the wheels rotate freely in the new axial 40 position into which they are placed by the operation of rod *M*. The stop and pin *56* are relatively arranged so that the wheel will be stopped in the zero position, or position which practically coincides with the end of the enlarged or amplified feed-space thereon. The 45 stop *55* is preferably constructed as a spring or automatically-retractible stop, for which purpose it may be formed or mounted on the end of a rod *57*, adapted to move in suitable 50 bearings, as indicated, and furnished at one end with a limiting-collar *58*, that limits its movement under the influence of the escape-wheels when the latter are moved to zero position. This collar *58* might be made adjustable on the rod *57*, and is in any case arranged to stop the movement of the rod *57* at the proper or zero position of the escapement-wheels. The retracting action is provided by means of a spring *59*, which surrounds the rod *57* and is held within a suitable case, as clearly indicated in the sectional view, Fig. 16. The slide *M* is moved by hand

backward in a direction to return the escapement-wheels to their position on the shaft *G'*, where they will engage with the pallets of the escapement. The stop and the escapement are properly arranged in such relative position to the escapement that in this reverse or return movement the wheel shall be in position to engage the pallets before the pin *56* leaves the edge of the stop *55*. By the retracting action of the spring the stop is withdrawn out of the way of the stop-pin *56* just as soon as the latter leaves the stop on movement backward to position for engagement by the escapement devices. Hence it will be out of the way of the pin if, after the printing of a few letters at the beginning of a line, the slide should be operated to draw the wheel back again, as would be done if the message should end with such few letters and it should be desired to reset the apparatus for beginning a new message. The stop when retracted is, however, in proper position to be engaged by the pin *56* when the latter has been rotated nearly the whole circle of rotation and is moved by the slide *M* axially, as before stated. The rod *M* operates upon the wheel *B* to withdraw it by means of a pin *61*, Fig. 9, or other device, which engages with the vertical arm of a bell-crank lever *62*, thereby lifting the long or horizontal arm of said lever, which engages the rocker *E²* in a manner to operate it in the same direction that the lifter *E⁴* and hook *E³* move it. 100

In order to keep the axial feed device from engaging with the paper when the circumferential feed is withdrawn by the operation of the slide *M*, said rod may be made to operate upon the lever *B³* by means of the lever *64*, Fig. 17, which takes under the yoke *28*, carried by said lever, and tends to raise the yoke end thereof when the slide *M* is operated, thus depressing or holding the end *B²* of the lever *B³* down. The lever *64* is conveniently controlled in its operation by a cone-shaped cam *66*, Figs. 8 and 9, on the slide, which normally holds the rear end of the lever lifted and the end which takes into the yoke *28*, Figs. 13 and 17, depressed, so as not to interfere with the normal operations of the axial feed device. When, however, the slide is operated the cam *66* allows the lever *64* to move under the action of a suitable spring *65* and to thereby engage with the yoke and hold the lever *B³* out of operative position. Suitable stops *67* applied to the rod *M* limit the motion thereof in both directions. There is also provided a suitable brake *68*, which is attached to an arm *69* secured to said rod and is adapted to engage with a portion of the train of wheels when the rod is operated to disengage the escapement-wheels from their escapement-pallet, Fig. 11. This brake is provided to prevent the wheelwork from running too rapidly to the zero-point. The brake may be applied to any wheel of the train, but preferably to the wheel *D*, as shown. The arm *69* is made as a spring to give a yielding action when the 110 115 120 125 130

rod is operated. It will be obvious that other mechanical devices of well-known construction might be interposed between the slide M or other controlling device and the two feed devices for holding them out of action and that other mechanical connections would be suitable for moving the escapement-wheels longitudinally to free them from the escapement.

- 10 To further assist in the operation of slipping a new tube into place we may combine with the latter a circuit-controller, which is operated by or at the same time with the said manual controller, so as to cut off current from 15 the magnets h and c', one or both. Such a circuit-controller may operate as a simple circuit-breaker placed in the direct circuit of the magnet or in the circuit of any device controlling said circuit. The circuit-controller 20 shown, Figs. 9 and 21, consists of a spring 70, that normally closes the circuit of the magnet by bearing against a stop 71. A pin 72 on the slide engages with the spring and draws it away from its stop when the slide is drawn 25 back to free the escape feed-wheel, thus breaking the circuit of the magnet. The circuit-controller serves to stop the operation of the printing-pad, which being a rapid succession of blows and forming at each blow a projection outside of tube might prevent a new 30 paper tube from being slid into position. It also effectually stops the paper-feed magnet from being actuated. Other forms of circuit-breaker could obviously be used for the same 35 purpose. In the manipulation of these devices the operator draws the slide M by one hand and at the same time slips the fresh paper tube forward by the other hand to position under the press-pad. In this action the 40 new paper tube displaces the one in use by sliding along the metal tube, from which it is subsequently removed. As the whole operation may be accomplished in the fraction of a second no material interruption to the printing 45 of the message need occur.

When the apparatus is operated at high speed it may be desirable to employ in connection with the type-wheel an automatic dogging or locking device, which shall come into 50 action as soon as the wheel is adjusted to position for printing any letter and positively lock or hold it in such position during the impression, as well as prevent it from being thrown out of such position in the adjusting 55 operation. This dogging device may be controlled over a circuit governed by the sunflower or distributer or by any other portion of the mechanism whose action is timed to bring the dog into position just at the instant 60 that the type-wheel reaches the adjusted position for the character. An electromagnet 90 may be used for operating the dog. The electromagnet 90 has an armature consisting of a rock portion 96, pivoted in the frame 65 above it, and having at the opposite ends of the magnet the arms 97, adapted to move to and from the poles of said magnet in a line trans-

verse to the axis of the magnet's core. Practically the same construction of armature is used for the armatures 12 of the electromagnets 1^a 1^b 2^a 2^b, &c. An arm 91, projecting from the rock-shaft 96 of the electromagnet 90, bears upon the head of a dogging-pin 92, while a spring 93, surrounding the pin, operates to hold the pin raised, as well as to retract the armature-lever. The point of the dog or pin is adapted to enter the holes in cylinder 95, forming a portion of the type-wheel shaft, which holes correspond in number and position to the number and position of the characters on the type-wheel, so that when the type-wheel is in position to print any character one of the holes will be beneath the point of the dogging-pin. The point of the pin normally just clears the surface of the cylinder in which the holes are formed. The point of the pin is conical in form, so that when the dog is forced downward it may find the hole and will operate to adjust the wheel to precise position for printing should it be slightly out of position when the dog is operated.

In the operation of the type-wheel the cylinder 95 moves freely under the point of the dog; but on the instant the adjuster devices 95 complete their action upon the type-wheel the dogging-magnet is energized and the point of the dog is thereby forced down, with the result already stated. The armature of the dogging-magnet may also have an arm 81, carrying a contact-spring 80, for controlling the operation of the press-magnet. The type-wheel may be inked by any desired means; but we prefer to employ an inked ribbon, which shall be automatically fed between the type-wheel 100 and the paper. Such a ribbon is indicated at 83, and is automatically fed from one to the other of two rotating ribbon-spools 84 over rollers to guide the ribbon in passing from one spool 84 to the other. This ribbon is conveniently fed by the action of a magnet of the apparatus, preferably one which operates at each impression.

The general operation of the apparatus is as follows: The parts being connected as already described, and as clearly indicated in the diagrams, the six pulses, alternately positive and negative, which accompany the transmission of each letter produce six vibrations of the distributer-escapement and one whole cycle of changes in the connections thereof, thereby closing in turn the connection to all the selector-relays U V W X Y and winding up with the closure at contact No. 6 of the restoring-circuit 99, which includes coils on the relays, whereby any tongue which may have been moved forward to bring into operation a type-wheel adjuster will be moved back ready for the next transmission. If any one of the first five pulses be prolonged, the relay whose connection at the sunflower is closed by that pulse will be operated, because the prolongation will operate magnet S and complete the break in the local connec-

tion of that relay. No other relays excepting those whose closure of connection at the sunflower is accompanied by a prolonged pulse will be operated. The relay or relays operated will close the circuits of the corresponding adjuster-magnets and thereby set the type-wheel to the desired position. The circuit of the press is closed, as already described, toward the termination of the cycle of changes and at such time that the press will not be thrown until the setting of the wheel into position for printing is accomplished. At the termination of each operation of the press—that is to say, on the back movement of its actuating-armature—it closes the circuit of the escapement-magnet h and produces a feed, as already explained, of the paper. Before the beginning of the next cycle the restoring-circuit comes into play to throw back the adjusters to normal position by bringing the selector-relays back to their normal contacts, thereby breaking the connection of the adjuster-magnets 1^a 2^a , &c., and closing those of magnets 1^b 2^b , &c.

25 What we claim as our invention is—

1. In a sunflower or distributer, a series of vibrating or rocking circuit breakers, in combination with an operating-wheel whose successive actuating lugs or spaces are differential to the spaces of the said circuit breakers so that all the circuit breakers shall be operated in a movement of the wheel equal to one of the spaces of the operating wheel.

2. The combination in a distributer, closing in rapid succession the branches of the circuit, of a series of rockers each having a circuit closing arm and an actuating arm, and a wheel having lugs or projections for engaging the arms of said rockers in succession to operate all the rockers in turn and then repeat the cycle of operation on partial rotation of the wheel.

3. In a sunflower or distributer, the combination with a vibrating or rocking circuit maker and breaker, of an actuating wheel connected to an escapement and adapted to produce a complete operation of the said circuit maker and breaker to cause a make and break of circuit or vice versa on movement of the wheel permitted by one movement of the escapement.

4. In a sunflower or distributer, a series of vibrating or rocking circuit controllers governing the several local circuits or branches, in combination with a step by step actuating wheel operating on said circuit controllers in succession as described to cause them to successively make and break the connection of the several local circuits or branches, each producing its make and break by a movement of the wheel one step, as and for the purpose described.

5. The combination, substantially as described, in a distributer, of a series of rock shafts each having an attached actuating arm, means for operating said arms in succession,

and a series of circuit closing arms attached respectively to said rock shafts for closing the several branches of a circuit in succession, said circuit closing arms being each adjustably fastened on its shaft so as to be capable of circumferential adjustment thereon independently of the actuating arm.

6. In a sunflower or distributer, the combination with a series of independently mounted circuit controllers and governing respectively the separate branches or circuits whose condition electrically is to be changed in succession and an actuating wheel moving step by step, operating on said circuit controllers to cause each to produce a complete change of electrical condition in its circuit, from normal and back to normal on movement of said wheel one step.

7. In a sunflower or distributer, the combination, of a series of circuit closers and breakers, a circuit branched therethrough and an actuating wheel having operating lugs or pins spaced as described to operate said circuit closers and breakers in succession, and to repeat the cycle of operations once for each movement of the wheel equal to the spacing of the lugs.

8. In a sunflower or distributer, the combination, of a series of rock shafts having actuating and circuit closing arms, a circuit branched through said circuit closing arms of an operating wheel having lugs or projections the spaces between which are less than the spaces between the actuating arms for the rock shafts.

9. In a sunflower or distributer, the combination, with a series of circuit closers and breakers, a circuit branched therethrough and an operating wheel having a series of actuating pins, an escapement wheel secured thereto, and one or more unison pins or stops connected to said escapement wheel.

10. The combination with the rock shaft, of the hubs or collars fastened thereon and each carrying two blade springs, one constituting a circuit closing arm and the other a retracting spring kept in tension by engagement with a stop through which electrical connection is maintained.

11. In a distributer or sunflower, the combination with a series of circuit makers and breakers, of a wheel having a series of actuating pins or lugs spaced as described to produce a complete cycle of circuit changes on movement over the space between two pins or lugs, and an escapement wheel whose teeth are spaced with reference to the number of contacts so as to produce a complete cycle of changes on movement of the wheel a whole number of teeth equal to one half the number of contacts.

12. The combination with the escapement, of a pair of polarized armatures of opposite polarity respectively, a double wound magnet core whose opposite polar ends are presented respectively to said armatures, and means for

causing a rapid succession of currents in alternation in the windings in said core, as and for the purpose described.

13. The combination of a pair of armatures 5 of opposite polarity respectively, a pair of double wound magnet cores between whose ends the armatures vibrate, and means for causing a rapid succession of currents in the two windings in said cores, as and for the purpose described.

14. The combination with two polarized armatures, of two actuating magnet cores whose opposite pole ends respectively embrace said armature, and a double winding for each of 15 said cores, one winding of each being included in circuit with a winding on the other, and means for causing currents to flow in opposite directions in the sets of windings alternately, as and for the purpose described.

20 15. The combination of the permanent magnet carrying an armature at each end, a pair of actuating magnet cores each having its opposite poles presented to said armatures respectively, and at a side thereof opposite the 25 poles of the other and windings for each of said cores through which currents are caused to flow in alternation but in direction to reverse the polarity of both cores simultaneously.

30 16. The combination with a sunflower or distributor operating step-by-step in response to a series of line pulses, of a double wound unison magnet the circuits of whose coils are closed alternately, and a unison stop carried 35 by an armature thereof and normally standing in position to stop the sunflower.

17. The combination with a unison stop, of a double wound or differential controlling magnet adapted to respond to a prolongation 40 or modification in a rapid succession of currents flowing through its coils alternately, and a unison stop carried by an armature thereof and normally standing in position to obstruct the movement of the mechanism after a succession of step-by-step movements thereof.

45 18. The combination with a receiving instrument having a unison stop device, of a differentially or doubly wound stop-controlling magnet, a relay to whose front and back 50 stops the two coils of said magnet are respectively connected, and a unison stop carried by an armature of the said stop controlling magnet and normally standing in position to arrest the mechanism.

55 19. The combination with a receiving instrument, of a polarized unison stop magnet differentially or doubly wound, and adapted to respond to a prolongation or modification in a rapid succession of currents flowing alternately through its two coils.

60 20. The combination with a distributor moving step-by-step, of a main line relay, a local through coils of the controlling magnets for said distributor, and a polarized unison stop 65 magnet in said local.

21. In a printing telegraph in which each

letter or character is transmitted by a definite number of impulses one or more of which is prolonged or modified, a synchronizing magnet responsive to a prolonged or modified impulse 70 following each transmission, and a stop controlled thereby and normally standing in position to arrest the mechanism.

22. In a printing telegraph in which each letter or character is transmitted by the same 75 number of impulses one or more of which is prolonged or modified, a synchronizing stop adapted to bring the receiving apparatus to rest after each transmission.

23. In a printing telegraph in which each 80 letter or character is transmitted by a definite number of alternately positive and negative impulses one or more of which are prolonged, a polarized synchronizing magnet responsive to a prolonged or modified impulse 85 of a determinate polarity following each series of impulses by which a letter or character is transmitted.

24. In a printing telegraph in which each letter or character is transmitted by a definite 90 number of alternately positive and negative impulses, a unison stop for the receiver adapted to bring the same to rest after each letter transmission, and a controlling polarized magnet for said stop responsive to a 95 modified impulse at the termination of a series of impulses the same in number as used in transmitting a letter or character.

25. The combination, substantially as described, of a sunflower or distributor moving 100 step-by-step in obedience to a series of main line pulses, a series of type adjusting magnets controlled thereby, a unison stop normally in position to stop the sunflower at the completion of each cycle of changes produced thereby, and a controlling magnet for 105 said stop responsive to a prolongation or modification in the final pulse of each cycle of main line pulses.

26. The combination with the receiving sunflower or distributor moving step-by-step in 110 obedience to a series of main line pulses, a unison stop adapted to stop the sunflower at the completion of each cycle of circuit changes produced thereby, and a stop magnet responsive to a prolongation or modification in the 115 final pulse of each cycle of main line pulses.

27. The combination with the receiving sunflower or distributor moving step-by-step in 120 obedience to a series of main line pulses alternately positive and negative, of a unison stop adapted to stop the sunflower at the completion of each cycle of circuit changes produced thereby, and a stop magnet responsive to a prolongation or modification in the 125 final pulse of each cycle of main line pulses.

28. The combination, substantially as described, of a double wound unison magnet and a double wound controlling magnet governing the circuits for the selecting relays, 130 both included in the same local circuit and each adapted as described to respond to a pro-

longation or modification in a rapid succession of currents flowing through their coils alternately.

29. The combination, substantially as described, of the distributor, the polarized escapement magnet therefor having a double winding, and a double wound magnet controlling the circuits of the selecting relays run by said distributor, said controlling magnet having its two windings included in the circuits of the windings for the escapement magnet and adapted to respond to a prolongation or modification in a rapid succession of currents flowing through the coils alternately.

30. The combination, substantially as described, in the same local circuit, of the double wound escapement magnet for the distributor, a double wound controlling magnet governing the circuits for the selecting relays connected to the distributor, and the double wound unison magnet for said distributor.

31. The combination, substantially as described, of the polarized escapement magnet having a double winding as described, means for closing the circuits of its coils or windings alternately in obedience to the main line pulsations, a unison magnet also having two windings included respectively in said local circuits, said unison magnet being adapted to respond to a prolongation or modification in the rapid succession of currents flowing through the coils of the polarized escape-

ment magnet, and a unison stop carried by an armature of said magnet and standing normally in position to arrest the escapement.

32. The combination, substantially as described, with an escapement, of two actuating circuits alternately closed by the main line pulsations, and a polarized unison stop magnet double wound and having its coils or windings included respectively in the said actuating circuits, said unison magnet being adapted to respond to a prolongation or modification in the rapid succession of currents by which the escapement is operated.

33. The combination, substantially as described, of a main line polar relay and a local circuit the two branches of which are closed in succession by movements of the main line relay, each branch of said circuit including, as described, one coil of an escapement magnet, of a unison magnet, and of a local circuit controlling magnet adapted to respond to a prolongation in the rapid succession of currents flowing through said branches successively.

Signed at New York, in the county of New York and State of New York, this 8th day of January, A. D. 1895.
